Inventor:

Peter L. Hedberg.
Asst. C. Gilman Atty.

UNITED STATES PATENT OFFICE.

PETER L. HEDBERG, OF CHICAGO, ILLINOIS, ASSIGNOR TO CHICAGO METAL WEATHER STRIP COMPANY, OF CHICAGO, ILLINOIS, A CORPORATION OF ILLINOIS.

METAL WEATHER-STRIP.

No. 928,194.

Specification of Letters Patent. Patented July 13, 1909.

Application filed March 24, 1909. Serial No. 485,519.

To all whom it may concern:

Be it known that I, PETER L. HEDBERG, a citizen of the United States, residing at Chicago, in the county of Cook and State of Illinois, have invented certain new and useful Improvements in Metal Weather-Strips, of which the following is a specification.

This invention relates to improvements in that class of metallic weather-strips which are designed to be secured to the upright guide-ways of window-frames for the sashes and to the stiles of said sashes, and it consists in certain peculiarities of the construction, novel arrangement, and operation of the various parts thereof, as will be hereinafter more fully set forth and specifically claimed.

The principal object of the invention is to provide weather-strips of the above-named character, which shall be very simple and inexpensive and well adapted for the purpose of preventing the passage of air and dust, rain and moisture in whatever position the window-sash or other element to which the strips are applied may assume in the frame, as well as to form guides for the movement of the sash-frames or other elements within the frame in such a manner as to prevent rattling and to compensate for any inequalities due to warpage or shrinkage, while requiring no especial skill to install them.

Various other objects and advantages of the invention will be disclosed in the subjoined description and explanation.

In order to enable others skilled in the art to which my invention pertains, to make and use the same, I will now proceed to describe it, referring to the accompanying drawing, in which—

Figure 1 is a horizontal sectional view of a portion of a window-frame and a part of the sashes thereof, showing them equipped with metallic weather-strips embodying one form of the invention; Fig. 2 is a detached perspective view of parts of the weather-strips employed in the construction illustrated in Fig. 1; Fig. 3 is a horizontal sectional view of a portion of a window-frame and a part of one of the sashes thereof, showing said parts equipped with a modified form of the weather-strips; Fig. 4 is a detached perspective view of the strips of the construction shown in Fig. 3; Fig. 5 is a horizontal sectional view of a portion of a window-frame and a part of one of the sashes thereof, showing said parts equipped with another modi-

fication in the construction of the strips; Fig. 6 is a detached perspective view of the modified form of strips shown in Fig. 5, illustrating them in the act of being disengaged; Fig. 7 is a horizontal sectional view of a portion of a window-frame and a part of one of the sashes thereof, showing strips embodying another modification applied thereto; and Fig. 8 is a detached perspective view of the strips shown in Fig. 7, illustrating them in the act of being placed in engagement with one another.

Like numerals of reference, refer to corresponding parts throughout the different views of the drawing.

The reference numeral 10 designates a portion of one of the uprights or side pieces of a window-frame which may be provided, as usual, with a parting-stop 11, an inside-stop 12 and an outside blind stop 13, which stops provide runways or guideways for the side-rails 14 of the sashes.

Referring now to Figs. 1 and 2 of the drawing, the reference numeral 15 designates the main body or portion of one of the outside strips, that is, of one of said strips which is secured by means of tacks or nails 16, or otherwise, to the inner surfaces of the vertical portions 10 of the window-frame and within the guideways thereof, which, as before stated, are produced by the stops 11, 12 and 13, or which guideways may be otherwise produced. This main or body portion 15 is secured vertically in the guideway thereof of the window-frame, and has at one of its edges an inturned flange 17 which is spaced from the inner surface of the part 15, and has at its other edge an inturned flange 18 which is likewise spaced from the portion 15, and is then reversed on itself as at 19 and bent outwardly to provide an extension 20 which may extend under the inside-stop 12 or outside-stop 13 depending on which side of the parting-stop the strips are used. This outside strip may be properly termed the female or receiving strip, and as shown in Fig. 2 of the drawing, the adjacent edges of the flanges 17 and 18 are spaced apart to receive the inwardly projecting portion 21 of the inner strip, which is located in a vertical groove 22 in the outer surface of the sash-rail 14 and may be secured thereto by means of tacks or nails 16, or otherwise. The inner strip, as is clearly shown in Fig. 2, as well as the outer strip, is formed of a single piece of metal, and

the inwardly projecting portion 21 of the inner strip is produced by folding the same upon itself, and has at each of its sides an outwardly extended flange 23 to fit under and slidely engage the flanges 17 and 18 of the outer strip while the sides of the inwardly projecting portion 21 will approximate or engage the adjacent edges of the flanges 17 and 18 of the outer strip.

- 10 Instead of using the strips constructed as shown in Figs. 1 and 2 of the drawing and above-described, strips of the construction shown in Figs. 3 and 4 may be employed, in which the construction is quite similar to 15 that of the above-described construction, except that the flange 18 of the main or body portion 15 has the reversed portion 19 and extension 20 employed in the other construction omitted, and the inner strip has one of 20 the outwardly extended flanges 23 omitted from the inwardly projecting portion 21, as is clearly shown in Fig. 4 of the drawing. When this modified construction is employed it is apparent that the single outwardly extended flange 23 will slidely engage the flange 18 on the body or main portion 15 while the inwardly projecting part 21 will be secured in a vertical slot 22 in the outer surface of the sash-rail by means of nails or 30 tacks 16, or otherwise.

In Figs. 5 and 6 of the drawing is shown still another modification, which consists in forming the parts of the same construction as shown in Figs. 1 and 2 and above-described, with the exception that one of the inturned flanges on the main or body portion 15, usually the flange 18 and its reversed portion 19, is pressed closely against the part 15 instead of being spaced therefrom, as shown 40 in Figs. 1 and 2 of the drawing. In the modification now under consideration the inner strip is provided as in the first above-described construction with an inwardly extended vertical portion 21 produced by being 45 bent back upon itself and provided on each of its sides with an outwardly extended flange 23, one of which is adapted for sliding engagement with the flange 17 and the main or body portion 15 while the other flange 23 50 on the inner strip is adapted to rest on the surface of the portion 19 adjacent thereto, as will be readily understood by reference to Figs. 5 and 6 of the drawing.

In Figs. 7 and 8 is shown another modified form in the construction of the weather strips, which consists in providing the outer strip with a main or body portion 15^a having at its sides inturned flanges 17^a and 18^a, the latter of which is pressed closely against the 55 inner surface of the portion 15^a while the flange 17^a is spaced therefrom, as shown. In this modified construction the extension 20 and part 19 shown in Figs. 2 and 6 are omitted from the outer strip, and the inner strip 60 is formed of the same construction as the in-

ner strip shown in Fig. 4, and has an inwardly extended vertical portion 21 provided with an outwardly extended flange 23 at one of its sides to slidely engage the flange 17^a and part 15^a while the free edge of that portion of the inwardly extended part 21 from which the flange has been omitted will lie in close proximity to the depressed flange 18^a and on the inner surface thereof.

In each of the constructions the inwardly extended portion 21 of the inner strip is fitted in a vertical groove 22 in the outer surface of the sash 14; and may be secured in place by means of tacks or nails 16, or otherwise, and as before stated, the outer strip in any of the 80 constructions may also be secured to the inner surface of the window-frame by means of tacks or nails 16, or otherwise.

From the foregoing and by reference to the drawing it will be clearly seen and readily understood that by employing weather-strips embodying my invention free and easy vertical movement of the sashes will be permitted, yet in such a manner as to prevent rattling due to shrinkage of the wooden parts and that any inequalities due to warpage of the wooden parts will be overcome or avoided by reason of the flexibility and slight resiliency of the weather-strips. Furthermore, it will be obvious that as the strips embodying the invention are adapted for sliding engagement with one another air, dust, moisture and water will be absolutely excluded or shut out. Furthermore, it is apparent that by using the constructions shown in Figs. 3 and 4, as well as in Figs. 7 and 8, the weather-strips may be detached from one another by removing the sashes inwardly or outwardly from the parting-stop 11, which can be done by simply removing the inner stop 12 or the outer stop 13, when said strips embodying said constructions are employed on both of the sashes, and it is mainly to permit such removal of the sashes and such disengagement of the strips that one of the flanges 23 is omitted from the inner strip as shown in Figs. 4 and 8, and mainly for a like purpose are the parts 18 and 19 in Fig. 6 and 18^a in Figs. 7 and 8 pressed against the parts 15 and 15^a, respectively.

In some instances the inner portion 21 of the inner strip may be simply located in the groove of the sash-rail without being secured therein, and one or both of the flanges 23 may be secured to the flanges of the outer piece, thereby permitting the sash to be moved on the inwardly extended portion 21 of the inner strip.

Having thus fully described my invention, what I claim as new, and desire to secure by Letters-Patent, is—

1. In a weather - strip, the combination with an outer strip consisting of a piece of sheet metal adapted to be secured vertically

or longitudinally to a suitable support and having an inturned flange at each of its side edges, one of said flanges being spaced from the main body of said strip, of an inner strip 5 consisting of a sheet metal piece formed with a vertically disposed inwardly extended portion adapted to be secured vertically or longitudinally to a support and having on each side of its portion adjacent to the outer 10 strip an outwardly extended flange one of which flanges is adapted to underlie one of said flanges on the outer strip and to slidably engage the same.

2. In a weather - strip, the combination 15 with an outer strip consisting of a piece of sheet metal adapted to be secured vertically or longitudinally to a suitable support and having at one of its side edges an inturned flange provided with a reversed portion and 20 outward extension and at its other side-edge with an inturned flange, of an inner strip consisting of a sheet metal piece formed with a vertically disposed inwardly extended portion adapted to be secured vertically or

longitudinally to a movable support and having on each side of its outer portion an outwardly extended flange. 25

3. In a weather - strip, the combination with an outer strip consisting of a piece of sheet metal adapted to be secured vertically 30 or longitudinally to a suitable support and having an inturned flange at each of its side edges, one of said flanges having an outwardly reversed portion provided with an outwardly projecting extension, of an inner 35 strip consisting of a sheet metal piece formed with a vertically disposed inwardly extended portion adapted to be secured vertically or longitudinally to a movable support and having on each side of its outer portion an 40 outwardly extended flange one of which is adapted to underlie one of the flanges on the outer strip and the other of which is adapted to overlie the other flange on said strip.

PETER L. HEDBERG.
